J. H. HASKELL, OF BALTIMORE, MARYLAND.

Letters Patent No. 69,991, dated October 22, 1867.

IMPROVED LEATHER-PUNCHING MACHINE.

The Schedule referred to in these Letters Patent and making part of the same.

TO ALL WHOM IT MAY CONCERN:

Be it known that I, J. H. HASKELL, of the city of Baltimore, in the county of Baltimore, and State of Maryland, have invented a new and improved "Punching Machine;" and I do hereby declare that the following is a full, clear, and exact description thereof, which will enable others skilled in the art to make and use the same, reference being had to the accompanying drawings, forming part of this specification.

The present invention relates to a machine for the punching of holes in a strip or band of leather or other material properly fed thereto; and the machine is the more especially designed for use in connection with the manufacture of hose from leather, and to that class of the same the edges of which overlap and are joined together by rivets. In the accompanying plate of drawings a machine for punching leather, etc., constructed according to my improvements is illustrated—

Figure 1 being a plan or top view of the same; and

Figure 2 a transverse vertical section, taken in the plane of the line *x x*, fig. 1.

Similar letters of reference indicate corresponding parts.

A, in the drawings, represents the bed or foundation-plate to the machine. B, two standards secured to bed-plate A. In these standards B, at their upper ends, a horizontal shaft, C, is arranged to turn. This shaft between the two standards B is provided with guides or flanges D susceptible of adjustment thereon, according to the distance apart which it is necessary for them to have to receive the width of the leather of which the hose is to be made that in my machine is to be punched. This shaft C at one end has a fixed and loose pulley for convenience in driving it, and at its other end has a pinion-wheel, E, fixed to it, which meshes into a gear-wheel, F, fixed to one end of a horizontal shaft, G, arranged to turn in bearings of standards H fixed to the bed-plate A. On the shaft G, between its two bearing points, are fixed two India-rubber or other equivalent wheels I, which are located near the centre line of the shaft, and upon the shaft, beyond the said wheels I, are pulleys or wheels J, similar in size and shape with each other. These pulleys J each carry a series of punches *a* that on both pulleys are equal distances apart. These punches *a* are to be of suitable form to punch leather or other material of a similar or equivalent nature. Directly below the shaft G, carrying the wheel punches, as above described, is located another shaft, L, that at each end is hung in suitable bearings of similar frames M. These frames at one end are hung to the inside of the uprights B, carrying guide-shaft C, and from thence extend under the shaft G, between the standards H therefor, to, and at their outer ends N rest by their set and adjustable screws O upon, inclined or wedge-shaped blocks P, that, by means of lever-handles Q, can be swung around upon their centre-pins R, and thus made to raise the said frames M up or allow them to fall or drop down, as the case may be. The shaft L carries between its two bearings wheels S and T T. The wheels S are in position for the punches of the punch-wheels to act upon them, as the shaft carrying the punching-wheel is revolved, and their peripheries are made of solder, zinc, pewter, copper, raw hide, or any other material which will not injure the cutting edges to the punches. The other wheels T T are made of India rubber, or other suitable and similar material, and are in position for the rubber wheels of the shaft G to act against and run in contact with them. The frames M, to which the lower shaft L is hung, carry also two feed-rollers U U between the punching-roller and the roller having guides for the leather to the machine, and also a roller, V, for the leather as it escapes from the machine to pass over and be guided therefrom.

With a machine constructed in its parts and arranged together as above described, the leather or other material to be punched is passed over the guide-roller C and between the feed-rollers to and between the rollers carrying the punching mechanism wherein the leather is necessarily punched. The guides to the rollers C serve to guide the leather straight to the punches, and by the rubber wheels the leather is held smooth and firmly in place as the punches are acting upon it, which punches serve to produce a feeding or drawing of the leather through the machine. By the manner in which the frames having the lower roller carrying the punching mechanism are hung they are susceptible of being operated through the wedge-blocks so that the lowering or raising of such shaft is greatly facilitated and the working of the machine rendered much easier and more convenient.

Having thus described my invention, what I claim as new, as far as it is now perfected, is—

1. The combination of the shafts G and L, carrying punching and rest-wheels, together with feed-wheels I, substantially as and for the purpose described.
2. I also claim the wedge-blocks P, in combination with the frames constituting the bearings to the shaft L, substantially as and for the purpose specified.

The above specification of my invention signed by me this 27th day of June, 1867.

J. H. HASKELL.
